United States Patent Office

Des. 219,764
Patented Jan. 19, 1971

219,764

TIRE

Rush M. Johnson, Jr., Wadsworth, Ohio, assignor to The
B. F. Goodrich Company, New York, N.Y., a corpo-
ration of New York

Filed Oct. 9, 1969, Ser. No. 19,489

Term of patent 14 years

Int. Cl. D12—14

U.S. Cl. D90—20

Fig. 1

FIG. 2

Fig. 3

FIG. 1 is a perspective view of a tire showing my new design;

FIG. 2 is a perspective view of one modified form thereof; and

FIG. 3 is a perspective view of another modified form thereof.

It is to be understood that the tread pattern, as shown for each embodiment, continues throughout the circumference of the tire.

I claim:

The ornamental design for a tire, substantially as shown and described.
